UNITED STATES PATENT OFFICE.

WILLARD C. COPE, OF WOODBURY, NEW JERSEY, ASSIGNOR TO E. I. DU PONT DE NEMOURS & COMPANY, OF WILMINGTON, DELAWARE, A CORPORATION OF DELAWARE.

EXPLOSIVE COMPOSITION.

1,390,671.

Specification of Letters Patent. Patented Sept. 13, 1921.

No Drawing.

Application filed June 13, 1918. Serial No. 239,774.

To all whom it may concern:

Be it known that I, WILLARD C. COPE, of Woodbury, in the county of Gloucester and in the State of New Jersey, have invented 5 a certain new and useful Improvement in Explosive Compositions, and do hereby declare that the following is a full, clear, and exact description thereof.

My invention relates particularly to detonating explosive compositions which are so treated that they will remain unchanged for long periods of time, but it relates especially to the treatment of dynamites of various kinds in such a manner as to prevent 15 deterioration of the same.

The object of my invention is to provide detonating explosive compositions, and especially dynamites, which have been so treated as to prevent leakiness in the same,—that is 20 to say, so as to avoid the exudation of the liquid constituents from the compositions upon standing. It has been found that detonating explosive compositions, and particularly dynamites, tend to become leaky after 25 a period of time, so that they become, for this reason, ineffective for the purpose for which they were made. I have discovered that this leakiness is caused by deterioration of the explosive composition, due to the 30 presence of living organisms. It is, therefore, the object of my invention to treat such explosive compositions, and particularly dynamites, in such a manner as to prevent the deterioration of the same, and in carrying 35 out my invention I treat said compositions in such a manner as to inhibit the growth of the living organisms therein.

Further objects of my invention will appear from the detailed description thereof 40 contained hereinafter.

While my invention is capable of being carried out in many different ways, for the purpose of illustration I shall describe herein only certain ways of carrying out the 45 same.

For example, I may proceed as follows in carrying out my invention. To a composition of the above character, I add a substance adapted to inhibit the growth of living organisms, as for example bacteria, fungi or yeasts, etc., or which will destroy said organisms. For this purpose I may add, by way of example, one or more of the following substances: salicylic acid, salt, sodium 50 salicylate, benzoic acid, sodium ben-

zoate, boric acid, borax, sodium fluorid, mercuric iodid, or a large quantity of sugar. The above mentioned aromatic acids or their salts not only inhibit the growth of living organisms but also have a plasticizing action, and make possible the addition to the gelatin dynamite of more wood pulp or other carbonaceous combustible material than would otherwise be the case, such addition resulting in a lower density gelatin 60 dynamite which remains sensitive to detonation for a longer period of time.

One example of a gelatin dynamite made in accordance with my invention would be comprised of:

Nitroglycerin	30.00%	by weight
Nitrocellulose	.8	% by weight
Ammonium nitrate	5.0	% by weight
Sodium nitrate	50.7	% by weight
Wood pulp	.5	% by weight
Wheat flour	9.0	% by weight
Sulfur	2.8	% by weight
Chalk	1.0	% by weight
Salicylic acid	.2	% by weight

In the above composition, a part of the 80 nitroglycerin can be replaced by a corresponding quantity, up to 2%, of a suitable nitro-aromatic compound, such for example as dinitrotoluol; the ammonium nitrate could be replaced with trinitrotoluol; the sodium nitrate could be replaced with potassium nitrate; the wood pulp could be substituted by another organic filling material; the wheat flour could be substituted by any other similar material, such for example as 85 vegetable ivory. Furthermore, many other substitutions could be made in the above composition, as said composition is cited 90 merely as one of many different examples.

As another example of a dynamite which 95 may be made in accordance with my invention, I may make use of the following:

Nitroglycerin	22.0%	by weight
Ammonium nitrate	26.0%	by weight
Sodium nitrate	38.0%	by weight
Sulfur	2.0%	by weight
Wood pulp	10.8%	by weight
Chalk	1.0%	by weight
Salicylic acid	.2%	by weight

In this composition, the nitroglycerin 105 ammonium nitrate, sodium nitrate and wood pulp may be substituted by other constituents in the same manner as described in connection with the first example above referred to. It will be understood that the sodium salt, 110

for example, of salicylic acid is the equivalent of free salicylic acid in my new composition.

Compositions which have been made in this way, that is to say by addition of the salicylic acid or one of the other preservative substances as above referred to, will be found to retain their form and condition the same as when first manufactured and 10 will no longer be subject to the leakiness that has been prevalent in the previous similar compositions which did not contain such preservatives.

While I have described my invention above 15 in detail, I wish it to be understood that many changes may be made therein without departing from the spirit of the invention.

It will be understood, thus, that the above examples are merely illustrative of the many 20 different kinds of explosive compositions which may be made in accordance with my invention.

I claim:

1. A detonating composition containing 25 an organic filling material and an aromatic acid adapted to inhibit the growth of living organisms.

2. A gelatin dynamite containing an organic filling material and an aromatic acid 30 adapted to inhibit the growth of living organisms.

3. A detonating explosive composition containing an organic filling material and a quantity of salicylic acid adapted to inhibit 35 the growth of living organisms.

4. A dynamite containing an organic filling material and a quantity of salicylic acid adapted to inhibit the growth of living organisms.

5. A gelatin dynamite containing an organic filling material and a quantity of salicylic acid adapted to inhibit the growth of living organisms.

6. An explosive composition comprising nitroglycerin, nitrocellulose, a nitrate, an 45 organic filling material, and a quantity of salicylic acid adapted to inhibit the growth of living organisms.

7. An explosive composition comprising nitroglycerin, nitrocellulose, a nitrate, an 50 organic filling material, sulfur, chalk, and a quantity of salicylic acid adapted to inhibit the growth of living organisms.

8. An explosive composition comprising nitroglycerin, nitrocellulose, a nitrate, wood 55 pulp, wheat flour, and a quantity of salicylic acid adapted to inhibit the growth of living organisms.

9. An explosive composition comprising nitroglycerin, nitrocellulose, a nitrate, wood 60 pulp, wheat flour, sulfur, chalk, and a quantity of salicylic acid adapted to inhibit the growth of living organisms.

In testimony that I claim the foregoing I have hereunto set my hand.

WILLARD C. COPE.
